CLAIM

The ornamental design for a support for a vacuum cleaner as shown and described.

DESCRIPTION

FIG. 1 is a front left perspective view of a support for a vacuum cleaner showing our new design.

FIG. 2 is a rear right perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines show portions of the design that form no part of the claimed design.

1 Claim, 8 Drawing Sheets
